RECEPTACLE HOLDER

Bernard J. Murphy, St. Paul, Minn.

Application July 17, 1947, Serial No. 761,578

3 Claims. (Cl. 248—311)

1

My invention relates to an improvement in receptacle holder wherein it is desired to provide a device for holding a garbage pail or the like in fixed predetermined position.

Considerable difficulty is experienced in holding garbage pails and similar receptacles in an upright position. Dogs and other animals often tip such receptacles to gain access to the contents. Means have been provided for holding the receptacles in an upright position. However, the bottom of the pail usually still rests upon the ground and the bottom of the pail is quickly deteriorated.

A feature of the present invention lies in the provision of a foldable rack for supporting a garbage pail or the like in spaced relation to the ground and in fixed upright position.

A feature of the present invention resides in the provision of a supporting rack having a pair of oppositely disposed clamps or jaws between which the receptacle may be resiliently engaged. This clamping means is easily detachable so that the receptacle can be easily and quickly removed therefrom. Furthermore as one of the supporting jaws is slidable and may be moved by engagement with the body of the receptacle, the receptacle may be easily clamped in place.

A feature of the present invention lies in the provision of a rack which may be bolted or otherwise affixed to any wall surface or similar upright support and which may fold up to require little space when not in use. Thus if the receptacle is used only during one portion of the year the device may be folded up when not in use.

These and other objects and novel features of my invention will be more clearly and fully set forth in the following specification and claims.

In the drawings forming a part of my specification:

Figure 1 is a perspective view of my receptacle support in position for use.

Figure 2 is a sectional view through my device, the position of the section being indicated by the line 2—2 of Figure 1.

Figure 3 is a sectional view through a detail portion of my device showing the construction thereof.

Figure 4 is a perspective view of a detail portion of my device.

The receptacle holder A includes an inverted generally U-shaped frame 10 which is designed to be bolted to a wall such as B and a second relatively vertical frame portion 11 pivotally connected thereto. The frame portion 11 forms a

2

supporting shelf and may be folded from the horizontal position shown in Figure 1 of the drawings to the upwardly inclined position not illustrated in the drawings. The frame member 10 is generally channel shaped in cross section in preferred form and includes a pair of upright portions 12 and 13 in parallel relationship which are connected by an integral top cross connecting member 14. If desired a cross brace 15 may be provided between the uprights 12 and 13 to brace the frame member 10 and to strengthen the same.

The frame member 11 includes a generally U-shaped frame member 16 having a pair of generally parallel sides 17 and 19 and a rounded connecting end 20. The frame member 16 may also be channel shaped in cross section if desired. The ends of the frame members 17 and 19 are connected by a cross connecting member 21 which acts as a brace between these ends. The sides 17 and 19 of the frame member 16 are spaced apart a distance proper to fit between the lower ends of the frame sides 12 and 13. A pair of aligned pivot bolts 22 extend through the lower extremities of the frame sides 12 and 13 and through the ends of the frame portions 17 and 19 to pivotally connect these elements along a generally horizontal pivot.

A pair of links 23 and 24 are pivotally connected together at 25 to connect the side 12 of the frame member 10 to the side 17 of the frame member 11. The link 23 is pivotally connected at 26 to the frame side 12 and the link 24 is connected at 27 to the frame side 17. A similar pair of links 29 and 30 are pivotally connected together at 31 and connect the other side 13 of the frame 10 to the side 19 of the frame 11. The link 29 is pivotally connected at 32 to the frame side 13 while the other link 30 is pivotally connected at 33 to the frame side 19. The links are of proper length to allow the frame member 11 to pivot to approximately right angles from the frame member 10. These links also permit the frame member 11 to fold upwardly into an upward inclined position if desired. The folding of the frame is particularly useful in shipping the frame, thus allowing the frame member 11 to be folded upwardly when necessary in which position the support takes less space.

A pair of braces 34 and 35 extend in parallel relation from the rounded forward end 20 of the frame member 11 to the cross member 21 at the other end thereof. These braces are shown as being angle shaped in cross section so as to form a firm support for the receptacle C which

may be placed thereon. A pair of brackets 36 and 37 are secured to the braces 34 and 35 near one end thereof, these brackets being provided with upwardly extending ends 39 and 40 respectively. An arcuated clamping segment 41 is supported between the two flanges 39 and 40. This clamping segment 41 is designed to engage against one side of the receptacle C to hold the receptacle in proper position on the support.

A cross member 42 is provided with hook shaped ends 43 which engage against the top horizontal flange of the braces 34 and 35. This cross member 42 forms a sliding support for the brackets 44 and 45 which support the arcuated clamping segment 46. A bolt 47 extends centrally through the cross member 42 as illustrated in Figure 3 of the drawings. This bolt forms a support for one end of a spring 49. The other end of the spring 49 is connected to a bolt 50 extending through the cross frame member 21. Thus the spring 49 urges the clamping segment 46 toward the fixed segment 41.

As best illustrated in Figure 4 of the drawings, the braces 34 and 35 are each provided with tongues or projections 51 which are bent from the body thereof and form a stop for limiting the movement of the cross member 42. The stops 51 are positioned properly so that a minimum size receptacle C may be placed between the segments 41 and 46.

In operation the receptacle C is placed upon the braces 34 and 35 and the lower edge of the receptacle is pulled forwardly until the rear side thereof engages forwardly of the clamping segment 41. The receptacle may then be pivoted into vertical position with the body of the receptacle clamped between the clamping segments 41 and 46 and resiliently held therebetween.

As an added convenience a chain 52 is indicated in dotted outline attached to the top cross member 14 of the frame 10 and to the cover 53 of the receptacle C. Thus the cover of the receptacle remains permanently attached to the support in normal operation.

In accordance with the patent statutes, I have described the principles of construction and operation of my receptacle holder, and while I have endeavored to set forth the best embodiment thereof, I desire to have it understood that obvious changes may be made within the scope of the following claims without departing from the spirit of my invention.

I claim:

1. A receptacle support comprising a shelf, a supporting means therefor, a pair of generally

parallel braces forming a part of said shelf, said braces being angular in cross section and having outwardly directed coplanar flanges, a pair of spaced brackets extending upwardly from said braces, a curved clamping member supported by said brackets, a cross member slidably supported on said braces, hook ends on said cross member engageable about said horizontal flanges of said braces to slidably support the same, brackets extending upwardly from said cross member, and a curved clamping member supported by said brackets.

2. A receptacle support comprising a shelf, a supporting means therefor, a pair of generally parallel braces forming a part of said shelf, said braces being angular in cross section, a pair of brackets extending upwardly from said braces, a curved clamping member supported by said brackets, a cross member slidably supported on said braces, hook ends on said cross member engageable about a flange of said braces to slidably support the same, brackets extending upwardly from said cross member, a curved clamping member supported by said last named brackets, and spring means urging said cross member toward said first named brackets.

3. A receptacle support comprising a shelf, a support means therefor, said shelf including a frame having a rounded extremity, a pair of braces extending from said rounded extremity to the opposite end of the frame, a pair of brackets extending upwardly from said braces, a curved clamping member supported by said brackets, a cross member slidably supported on said braces, hook ends on said cross member engageable about the outer edges of said braces to slidably support the same, brackets extending upwardly from said cross member, a curved clamping member supported by said last named brackets, and spring means urging said cross member toward said first named brackets.

BERNARD J. MURPHY.
